(57) **CLAIM**

The ornamental design for an electronic crossover housing, as shown and described.

DESCRIPTION

FIG. 1 is a perspective view of an electronic crossover housing showing the new design;

FIG. 2 is a top view thereof;

FIG. 3 is a bottom view thereof;

FIG. 4 is a right-side view thereof;

FIG. 5 is a left-side view thereof;

FIG. 6 is a front view thereof; and,

FIG. 7 is a rear view thereof.

The broken lines are for environmental purposes only and do not form any part of the claimed design.
